Ernest Zadig
By J. Jochum & Son Attl.

UNITED STATES PATENT OFFICE.

ERNEST ZADIG, OF CHICAGO, ILLINOIS.

SIGNAL DEVICE FOR VEHICLES.

1,356,585.

Specification of Letters Patent. Patented Oct. 26, 1920.

Application filed November 3, 1919. Serial No. 335,348.

To all whom it may concern:

Be it known that I, ERNEST ZADIG, a citizen of the present Government of Germany, residing at Chicago, in the county of Cook and State of Illinois, have invented certain new and useful Improvements in Signal Devices for Vehicles, of which the following is a specification.

This invention relates to improvements in signal devices for vehicles, particularly adapted though not necessarily limited in its use with motor vehicles, and one of the objects of the invention is to provide an improved device of this character which will be self-contained and which embodies means whereby the signal may be operated and controlled in its operation by the inertia of a moving mass and independent of the operation of any of the other parts of the vehicle.

A further object is to provide improved means to prevent the undesired operation of the signal device by the spring action of the vehicle during its ordinary course of travel.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which;

Figure 1 is a front elevation of a signal of this character constructed in accordance with the principles of this invention and showing the parts in one position.

Fig. 2 is a sectional view taken on line 2—2, Fig. 4 and with parts broken away to show the circular lens.

Fig. 3 is a sectional view taken on line 3—3, Fig. 1 and with parts broken away to show the circular lens.

Fig. 4 is a sectional view taken on line 4—4, Fig. 2.

Referring more particularly to the drawing the numeral 10 designates generally a housing of any desired size and configuration in which the signal device is arranged and this housing is supported in any desired or suitable manner preferably by means of a bracket 11 adapted to engage and be secured to the tail light support of a motor vehicle.

Within the housing thus constructed is a

light or lamp 12 which receives current from any suitable source, and in front of the lamp is arranged a window 13 through which the rays of the lamp will be visible at all times when the light is lighted similar to the ordinary tail light.

The housing is provided with an open front 14 of any desired size and configuration and arranged in line with the opening 14 and against the back of the housing is a signal 15 preferably comprising the letters of a word such as "Stop" and are arranged so that they will be visible from the outside of the housing during the day time and at night when the light 12 is lighted, the rays from the light will also be directed against this signal.

Operating so as to be moved across the opening 14 are a plurality of shutters 16 which may be constructed of any suitable material and these shutters are preferably pivotally mounted by their ends as at 17 in suitable bearings and are connected by means of a link or connecting bar 18 which has pivotal engagement 19 with each of the shutters so that the shutters will be moved simultaneously about their pivot to expose or conceal the signal 15.

The shutters 16 may be provided with a series of openings 20 therethrough and which openings are arranged in any suitable manner preferably so as to form the letters of another word or signal such as "Go" and the openings are provided so that the light rays from the lamp 12 will be visible therethrough when the shutters are in a position to conceal the signal 15.

The shutters 16 are adapted to be operated by the inertia of a movable mass and this mass also serves as a means for maintaining the shutters 16 in their adjusted position. This may be accomplished in any desired or suitable manner but preferably by means of a movable mass 21 which in the present exemplification of the invention is indicated as mercury, although it is to be understood that any suitable moving mass may be employed for the purpose.

This mass 21 is arranged within a closed cylinder or chamber 22 which is of a length considerably greater than the length of the mass and the cylinder is mounted for pivotal movement intermediate its ends preferably by means of a yoke or bracket 23 pivotally mounted as at 24 upon a fixed or rigid support 25, in such a manner that when inertia

is imparted to the mass 21 the mass will move from one end or side of the chamber 22 to the other side and thereby cause the chamber to be moved about its pivot 24.

5 In order that this motion caused by the inertia of the mass which constitutes a prime mover, may be imparted to the shutters 16, the shutters are operatively connected with the chamber in any suitable manner such, 10 for instance, as by means of an arm 26 connected with the yoke or bracket 23. A link 27 is pivotally connected as at 28 at one end to the arm 26 and is pivotally connected by its other end to a crank arm 29 which latter 15 is in turn connected with one of the shutters 16. It will, therefore, be manifest that when the chamber 22 is given its shifting or tilting movement by the inertia of the mass 21, the arm 26 and link 27 will impart this motion to the shutters 16 and cause them to open or close according to the direction of movement of the mass, to expose or conceal the signal 15.

In order to overcome the inertia of the 25 mass 21 under predetermined conditions, such as the vertical movement of the vehicle during its travel due to the action of the vehicle springs, and thereby maintain the shutters 16 in their proper position, any suitable 30 means may be provided, such, for instance, as a brake 30 which may be in the form of a yoke, mounted for vibratory movement preferably by means of a spring arm 31 secured to a rigid portion of the device. This yoke 35 30 is adapted to stand astride of a surface 32 which is connected with the chamber 22 for movement therewith and the periphery of the surface 32 may be roughened or knurled as desired. With this construction it will be 40 seen that as the vehicle vibrates by the spring or bumping action the brake 30 will also vibrate with respect to the surface 32 and this will cause first one and then the other of the arms of the brake to engage the 45 surface 32 creating a braking action upon the surface 32 to maintain the parts in their proper position, yet the friction of the brake upon the surface is not sufficient to prevent the inertia of the mass 21 from operating 50 the signal when the vehicle is starting or stopping. Normally, the brake 30 is preferably entirely out of contact with the surface 32.

The casing 10 may be provided with a 55 bracket 33 which constitutes a support for the license plate 34 and the casing is provided with a suitable slot or opening 35 adjacent the license plate 34 so that the rays from the lamp 12 will be directed against 60 the license plate.

Obviously a transparent closure 36 may be provided for the opening 35.

With this improved construction it will be manifest that the operation of the signal 65 is entirely independent of the operation of

any of the other parts of the vehicle, the signal being operated entirely by the inertia of the moving mass 21, which latter constitutes the initial or prime mover for actuating the remaining parts of the signal and 70 which parts are in turn connected with the shutters 16.

While the preferred form of the invention has been herein shown and described, it is to be understood that various changes may 75 be made in the details of construction and in the combination and arrangement of the several parts, within the scope of the claims without departing from the spirit of this invention. 80

What is claimed as new is:—

1. A signal device for vehicles embodying a housing having an opening in one wall thereof, a shiftable element mounted for movement across the opening, a shiftable support, a mass carried by the support for movement with respect thereto and constituting a prime mover, whereby the inertia of the said mass will shift the said support, said support and said element being supported independently of each other, means whereby the said element will be positively actuated by the movement of the said support under the influence of the inertia of the said mass, and a brake device for restraining 95 the said support against shifting movement under the influence of the spring action of the vehicle.

2. A signal device for vehicles embodying a housing having an opening in one wall 100 thereof, a shiftable element mounted for movement across the opening, a shiftable support, a mass carried by the support for movement with respect thereto and constituting a prime mover, whereby the inertia of the said mass will shift the said support, said support and said element being supported independently of each other, means whereby the said element will be positively actuated by the movement of the 105 said support under the influence of the inertia of the said mass, and a brake device for restraining the said support against shifting movement under the influence of the spring action of the vehicle, said brake device embodying a braking surface connected with the said support and a vibrating brake element coöperating with the said surface.

3. A signal device for vehicles embodying a signal proper, a movable mass, means 120 whereby the inertia of said mass will automatically actuate the signal, and brake mechanism operating automatically to overcome the said inertia to maintain the signal against operation under the influence of the 125 spring action of the vehicle.

4. A signal device for vehicles embodying a signal proper, a movable mass to which inertia is imparted solely by the motion of the vehicle, means whereby such in- 130

- ertia constitutes the prime mover for actuating the signal, and brake mechanism operating to overcome such inertia under the influence of the spring action of the vehicle 5 to maintain the signal against operation.
5. A signal device for vehicles embodying a changeable signal embodying a shiftable element, a movable mass to which inertia is imparted by the motion of the vehicle, 10 means whereby such inertia will constitute the prime mover for shifting said element, the said means embodying a shiftable support with respect to which the mass is movable to shift the support, means responsive 15 to the shifting movement of the said support for shifting said element, and means operating to maintain the said support against shifting movement under predetermined conditions.
- 20 6. A signal device for vehicles embodying a changeable signal embodying a shiftable element, a movable mass to which inertia is imparted by the motion of the vehicle, means whereby such inertia will constitute the prime mover for shifting said element, the said means embodying a shiftable support with respect to which the mass is movable to shift the support, means responsive 25 to the shifting movement of the said support for shifting said element, and means operating to maintain the said support against shifting movement under predetermined conditions.
- 30 7. A signal device for vehicles embody-

ing a changeable signal embodying a shiftable element, a movable mass to which inertia is imparted by the motion of the vehicle, means whereby such inertia will constitute the prime mover for shifting said element, the said means embodying a shiftable support with respect to which the mass is movable to shift the support, and a vibratory brake device for maintaining the said support against shifting movement under predetermined conditions. 40

8. A signal device for vehicles embodying a housing, a signal device therein and visible from the outside side of the housing, means within the housing for illuminating 50 the signal, a movable signal device arranged to conceal or expose the first recited signal, a movable mass to which inertia is imparted by the movement of the vehicle, means whereby such inertia will operate to shift 55 the second recited signal device to conceal or expose the first recited signal, means whereby the light rays of the illuminating means will be visible through the second recited signal device when the latter is in a 60 position to conceal the first recited signal device, and a license plate holder, there being an opening in the wall of the housing adjacent the said holder through which the light rays pass. 65

In testimony whereof I have signed my name to this specification, on this 29th day of October, A. D. 1919.

ERNEST ZADIG.
